UNITED STATES PATENT OFFICE

150,672

DESIGN FOR AN AIRPLANE

Derwood A. Beck, Seville, Ohio, assignor to Good-year Aircraft Corporation, Akron, Ohio, a corporation of Delaware

Application October 8, 1946, Serial No. 133,830

Term of patent 14 years

(Cl. D71—1)

To all whom it may concern:

Be it known that I, Derwood A. Beck, a citizen of the United States, residing at Seville, county of Medina, and the State of Ohio, have invented a new, original, and ornamental Design for an Airplane, of which the following is a specification, reference being had to the accompanying drawings, forming part thereof.

Fig. 1 is a top plan view of the airplane, showing my new design;

Fig. 2 is a side elevational view thereof;

Fig. 3 is a front elevational view thereof; and

Fig. 4 is a top perspective view of the airplane in flight.

The characteristic features of my design reside in the portion shown in full lines in the drawings.

I claim:

The ornamental design for an airplane, as shown and described.

DERWOOD A. BECK.
